US00D794042S

(12) **United States Design Patent** (10) **Patent No.:** **US D794,042 S**
Sung et al. (45) **Date of Patent:** **** Aug. 8, 2017**

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Sophia H Sung**, Irvine, CA (US); **Jonathan P. Gaiser**, Sunnyvale, CA (US); **Chris Turkstra**, San Jose, CA (US); **Maxel J. Keene**, Sunnyvale, CA (US); **Heejin Ko**, Bucheon-si (KR); **Jangwon Seo**, Seoul (KR); **Jae Julian**, Seoul (KR); **Yoojin Choi**, Seoul (KR)

(73) Assignee: **SAMSUNG ELECTRONICS CO., LTD.**, Suwon-si (KR)

(**) Term: **15 Years**

(21) Appl. No.: **29/550,210**

(22) Filed: **Dec. 31, 2015**

(51) LOC (10) Cl. **14-04**

(52) U.S. Cl.

USPC **D14/485**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The broken lines in the drawings illustrate the display screen or portion thereof with graphical user interface that form no part of the claimed design.

1 Claim, 1 Drawing Sheet
